UNITED STATES PATENT OFFICE.

EDWARD RIVETT, OF BOSTON, MASSACHUSETTS.

DESIGN FOR A STAKING-TOOL.

SPECIFICATION forming part of Design No. 19,637, dated February 4, 1890.

Application filed December 21, 1889. Serial No. 334,567. Term of patent 14 years.

To all whom it may concern:

Be it known that I, EDWARD RIVETT, a citizen of the United States, residing at Boston, in the county of Suffolk and State of Massachusetts, have invented and produced a new and original Design for Staking-Tools; and I do hereby declare the following to be a full, clear, and exact description of the same, reference being had to the accompanying drawings, forming a part thereof.

This design has for its object to provide a novel form of staking-tool; and the leading features thereof consist in a rectangular base having one end circular and provided with concave surfaces between its horizontal top and bottom sides, a rectangular post arising from the top of the base and a goose-neck part projecting from the post.

In the accompanying drawings, Figure 1 is a perspective view of the staking-tool formed

according to my design, and Fig. 2 is a top plan view of the same.

In the drawings, the letter A indicates the rectangular base, having one end circular, and *a a a* indicate the concave surfaces between the horizontal top and bottom sides of the base. The rectangular post B rises from the top side of the base, and the goose-neck part *b* projects from the upper end of the post and is provided at its extremity with a sleeve *b'*.

What I claim is—

The design for a staking-tool, substantially as described and shown.

In testimony whereof I have affixed my signature in presence of two witnesses.

EDWARD RIVETT.
